UNITED STATES PATENT OFFICE.

GEORGE W. FOSTER, OF PROVIDENCE, RHODE ISLAND, ASSIGNOR TO UNIVERSAL WINDING COMPANY, OF BOSTON, MASSACHUSETTS, A CORPORATION OF MASSACHUSETTS.

WINDING-MACHINE.

1,347,626.

Specification of Letters Patent.

Patented July 27, 1920.

Application filed October 7, 1916. Serial No. 124,373.

To all whom it may concern:

Be it known that I, GEORGE W. FOSTER, a citizen of the United States, residing at Providence, in the county of Providence, State of Rhode Island, have invented certain new and useful Improvements in Winding-Machines, of which the following is a specification.

My invention relates to improvements in winding machines and particularly to cone-winders of the friction-drive or drum-wound type. The object of my improvement is to control the position of the cone-holder or winding-mandrel in relation to the traverse 10 of the thread-guide during its recession from the driving-drum or drive-roll as the cop builds up thereon, whereby the formation of the cone is determined and regulated in accordance with the preferred shape and proportions.

My improvements are directed especially to that type of cone-winder which operates to increase the taper of the cone from start to finish of the winding, whereby the package 20 has a greater "conicity" on its outside than at its core, and wherein the ends of the cone assume a concavo-convex shape. The usual practice with this method of winding is to increase the conicity of the package 25 to a considerable extent in order to attain the maximum advantages of easier delivery of the yarn in unwinding it therefrom; but in most cases this change in the taper of the package has a tendency to shape 30 the small end of the cone with too great a degree of concavity consistent with stability and firmness of the yarn-mass. That is to say, if the nose end of the cone becomes abnormally concaved or hollowed out the overhanging ends of the yarn layers composing 35 the body of the cone will not have sufficient support to hold them in place and are liable to slough off or break down, thereby interfering with the delivery of the yarn when 40 the cone is unwound.

My present improvement is intended particularly to correct this condition, that is to prevent the soft, unstable formation of the yarn-mass at the nose end of the cone by 45 regulating its concavity within prescribed limits as adapted to give the best results. The method of attaining this object consists in controlling the relative displacement between the cone-holder and the path of traverse of the thread-guide throughout the

building of the cone, whereby the layers of winding are prevented from advancing at a too rapid rate toward its nose or apex end as more fully explained hereinafter.

The manner and means for accomplishing this result are fully described in the following specification, illustrated by the accompanying drawings, in which like reference characters designate like parts. In the drawings:—

Figure 1 is a plan view of the essential elements of a well known type of friction-drive cone-winder, showing my improvement applied thereto;

Fig. 2, an end view of the same;

Fig. 3, a plan view of a slightly modified form of cone-holder support with my improvement shown in connection therewith;

Fig. 4, a plan view of a still different arrangement of the cone-holder support; and

Figs. 5, 6, 7 and 8, diagrammatic views indicating the method of operation of my improved device, and the result it effects in the formation of the cone.

Referring first to Figs. 1 and 2, D designates the cylindrical driving-roll or drum from which the cone or package is driven, and G the traversing thread-guide which is reciprocated longitudinally of the cone-holder C to deposit the yarn in place thereon. The drive-roll D may be rotated through any suitable means, as usually provided, but not herein shown or described; and the thread-guide G is preferably mounted on a horizontal rod or bar B which is reciprocated from a cam, rock-shaft or the equivalent as well known in the art. As shown in Fig. 1, the cone-holder C on which the package is wound comprises a tapered mandrel rotatably mounted on a spindle S held fast at its end in a hinged arm A. The arm A is pivotally mounted on a horizontal rod or shaft F to adapt the cone-holder C to swing upwardly from the drive-roll D as the package increases in diameter. As here illustrated the arm A is constructed in two parts *a* and *a'*, with the spindle-support *a'* swiveled in the end of the main part *a* to allow for an increase in the angle of inclination of the cone-holder C with respect to the axis of the drive-roll D as it recedes therefrom.

The thread-guide G is preferably curved around the periphery of the drive-roll D to bring its upper end in position adjacent the

point of contact of the cone-holder C on the roll and is slotted at g to receive the yarn y . The yarn y leads from its source of supply, not here shown, through the slot g , and as 5 the guide G is reciprocated longitudinally of the drive-roll D it acts to traverse the yarn along the holder or mandrel C.

The above described arrangement is common to machines of the present type now 10 in general use in the winding art and in most instances additional mechanism is provided for depositing a greater mass of yarn at the base end of the cone than at its apex end to effect its building with a gradually increasing taper or conicity. This 15 last result may be accomplished in several ways: For instance in my U. S. Patent No. 766,175, granted Aug. 2, 1904, there is described a method of increasing the angle 20 or pitch of the coils of winding from the base to the nose end of the cone throughout its building to deposit a thicker body of yarn toward the larger end of the package. This result is accomplished by providing for a differential speed of traverse 25 of the thread-guide as explained in my U. S. Patent No. 747,404, granted Dec. 22, 1903. That is to say, the speed of movement of the guide is increased as it moves toward 30 the apex of the cone, and retarded in the opposite direction, whereby the helical coils of winding are given a greater angle of inclination at the small end of the cone so that the yarn is laid more compactly 35 and builds up faster at the base than at the nose.

Another method of increasing the taper of the cone during its building is described in my pending application for U. S. Patent, 40 Serial No. 79,412, filed Feb. 19, 1916. This consists in progressively shortening and lengthening the traverse of the yarn at the apex end of the cone at intervals of the winding, whereby certain of the layers are 45 stepped back toward the base of the cone, resulting in depositing a greater thickness of yarn at this end and a consequent increase in the taper on the outside of the cone.

50 Either of the above described methods, or any other, may be employed in connection with the winding apparatus herein shown and it will be obvious that as the taper of the cone increases during its building its mandrel or holder C must be allowed to tilt in order to maintain the surface of the winding constantly in contact with the periphery of the drive-roll D. The swiveled mounting of the outer end of 55 the arm A, Figs. 1 and 2, provides for this tilting action of the cone-holder C, as the axis of the cone increases its angle of inclination to the surface of the drive-roll D, and it is to be noted that another effect is 60 the arm A, Figs. 1 and 2, provides for this tilting action of the cone-holder C, as the axis of the cone increases its angle of inclination to the surface of the drive-roll D, and it is to be noted that another effect is 65 thereby produced. As the base end of the

cone-holder C swings upwardly at a faster rate than that of the small end, with the axis of the cone becoming more and more inclined to the drive-roll D, the point of the cone-holder will normally be gradually 70 withdrawn or displaced along the roll D in the direction indicated by the arrow 2, Fig. 1. In the present type of machine, where the cone-supporting arm A swings upwardly in a fixed plane the cone-holder 75 C is carried in such a path that succeeding layers of the cone are deposited in advanced relation one to another toward its apex end. That is to say, the traverse of the yarn is displaced away from the base end 80 of the cone causing the layers of yarn to overhang at the apex end and resulting in the concavo-convex shape of the ends of the finished package as illustrated by dash lines in Fig. 5. This effect of concavo-convexly shaping the ends of the cone is common to substantially all types of cone-winders operating on the drum or friction-drive principle since the cone-holder must always recede from the drive-roll with its 85 axis inclined thereto. A normal amount of convexity at the base of the cone is of advantage since it provides for setting the package on its end in delivering the yarn therefrom without hindrance in drawing off 90 the coils.

In machines of the type in which the side of the cone-holder remains parallel with the surface of the drive-roll during its recession therefrom the ends of the yarn layers 100 will be disposed in planes perpendicular to the surface of the cone-holder. In other words, the ends of the layers will align in planes at substantially right-angles to a line drawn through the surface of the cone-holder longitudinally of its axis, see full lines in Fig. 8. When, however, the cone-holder C is constantly tilted, to increase the angle of inclination of its axis to the drive-roll, see Fig. 5, then the layers of 105 winding will be displaced to a greater extent away from the base of the holder giving the result illustrated graphically by the dot-and-dash lines in Fig. 8. Fig. 5 illustrates the cone-holder C carried by an arm 110 A, as shown in Figs. 1 and 2, with means to allow for the tilting of its axis as it recedes from the drive-roll D. This angular displacement of the cone-holder C is caused by the increase in taper of the outside of the cone, as previously explained, and the effect of this on the ends of the cone is as follows: As the small end of the cone-holder C tilts downwardly during the upward movement of the arm A the effect 115 will be to displace the whole mandrel bodily in the direction indicated by the arrow 2, Figs. 1 and 5. In other words, as the arm A swings upwardly in a right-line path, as indicated at X—X, Fig. 5, the tilting 120

of the cone-holder C about its axis of support α has the effect of withdrawing it rearwardly along the axis of the drive-roll D. This longitudinal, receding movement of the holder C causes an increased displacement of the layers of winding toward the apex end of the cone and consequently increases the convexity of its base and the concavity of its nose, as represented by the dash-lines in Fig. 5, which illustrate the form of the completed package. As before indicated a slight degree of concavo-convexity at the ends of the cone is desirable; but when the nose end of the cone becomes abnormally concaved, in increasing the taper of the outside of the package to the desired extent, it results in an unstable structure of the yarn-mass without sufficient support for the outer layers to prevent them from falling over or becoming displaced. In other words, if the apex end of the cone is abnormally concaved or hollowed out the coils of winding will not be properly supported and held in place and the nose of the cone will become soft, spongy and malformed, preventing a free delivery of the yarn and detracting from the appearance and utility of the finished package.

To correct this condition, that is the abnormal concavity of the nose of the cone, I have devised a means for preventing the longitudinal recession or rearward displacement of the cone-holder with respect to the path of traverse of the thread-guide. Referring again to Figs. 1 and 2, the arm A has its hub α^2 bored to fit the longitudinal rod F on which it pivots and on the top of the hub is secured a curved plate P. The rod F is usually supported in fixed brackets or standards, one of which is shown at R, and the plate P overhangs the side of the hub α^2 and extends above the top of the hub or bearing r on the bracket R. Formed in the overhanging portion of the plate P is an inclined cam-slot p, preferably of slightly arcuate contour, and a pin p' driven into the hub r projects through the cam-slot p in engagement with the curved sides thereof. The hub α^2 of the arm A is free to slide on the rod F during its pivotal movement about its axis and as the arm swings upwardly the pin p' will act on the cam-plate P to move the arm bodily in the direction indicated by the arrow 3, Fig. 1. This lateral, sliding movement of the arm A acts to displace the cone-holder C longitudinally in the same direction and the effect of this on the formation of the cone is as follows:

Referring to Fig. 6, as the yarn is built up on the tapered mandrel or cone-holder C the arm A swings upwardly while maintaining the surface of the winding constantly in contact with the periphery of the drive-roll D. Meanwhile the axis of the cone-holder C gradually assumes a greater inclination to

the drive-roll D, to provide for the increase in taper on the surface of the winding, this increasing conicity being effected by depositing a thicker mass of yarn at the base of the cone in any preferred manner as previously explained. To compensate for this tilting movement of the cone-holder and the consequent tendency to displace it along the drive-roll D in the direction indicated by the arrow 2, Figs. 1 and 5, the cam-plate P comes into action to shift the arm A in the opposite direction. The inclination or eccentricity of the cam-slot p is preferably arranged to cause the pivoted support α' of the cone-holder C to travel in an arcuate path, represented by line Z-Z, Fig. 6, and to displace the cone-holder C to such an extent that the ends of the layers of the winding fall in planes perpendicular to the side of the holder. In other words, the position of the cone-holder C is maintained in such relation to the ends of travel of the thread-guide, indicated at z-z, Fig. 6, that the ends of the layers of winding will aline in perpendicular relation to the surface of the holder. It has been found in practice that with this arrangement of the mechanism the relatively slight concavo-convexity of the ends of the cone provides the improved results desired, but it will be obvious the degree of concavity and convexity may be varied slightly within certain limits if desired. Fig. 8 illustrates the improved form of cone produced by the present invention as compared graphically with the usual conformation. In this diagram the full lines represent the outline of the cone with the preferred degree of concavo-convexity at its ends, while the dot-and-dash lines show an extreme concaved formation of the cone which is to be avoided.

Fig. 3 illustrates a slightly modified form of support for the cone-holder C. As here shown the outer end of the hinged arm A is constructed as a fork or yoke A' swiveled on a rod or pivot k held in the main portion a. The cone-holder or mandrel C is provided with pintles or trunnions t, t at either end journaled in bearings at the ends of the arms α^3 , α^3 of the yoke A'. As the arm A swings upwardly on the fixed rod F the yoke A' swivels on the pivot k to provide for the tilting of the cone-holder C as the surface of the winding changes in taper. With this arrangement of the cone-holder support the cam-slot p is formed in the hub α^2 of the arm A while the pin p' is driven into the rod F. The pin p' will therefore act directly on the hub α^2 to shift the arm A and the cone-holder C in the manner and for the purpose as before explained.

Fig. 4 shows a still further modification in the arrangement of the cone-holder support and this construction I regard as the preferred embodiment of my present inven-

4

tion. The arm A has substantially the same arrangement as shown in Figs. 1 and 2, with the cone-holder spindle S hinged to the end of its swiveled extension *a'* at *s*. The cone-holder C is also supported at its opposite, apex end by a separate arm E. The arm E is pivoted on a fixed rod F', arranged parallel with and below the rod F, and is jointed at *e* to provide the hinged latch or extension 10 E'. The latch E' may be swung back to allow for the insertion of the end of the cone-holder in its bearing or for its withdrawal therefrom in applying or removing the cone-tube from its support. A spring *e'* tends to 15 maintain the two parts of the arm E in alinement to retain the cone-holder in place in its bearings and the latch E' moves with and as a part of the main pivoted portion E. The cam-plate P is applied to the arm 20 A which is free to slide on its pivot-rod F, but the arm E has no sliding movement, being held on its rod F' by the collars *f*, *f*. As the arm E is shifted laterally, however, as before explained, the slight, longitudinal 25 displacement of the cone-holder C at its small end is provided for by the swinging of the latch E' on its hinge *e*.

The purpose of pivoting the arm E on an axis below that of the arm A is to provide 30 for different paths of movement of the base and apex ends of the holder C. Through this improved arrangement the line of contact of the surface of the winding with the periphery of the drive-roll D is maintained 35 substantially parallel with the axis of the roll. Where both ends of the cone-holder swing on the same center and follow the same arc the cone will be twisted laterally in relation to the drive-roll during its re- 40 cession therefrom. That is to say, the line of contact of the cone on the drive-roll will not be maintained in a plane parallel with the axis of the roll, but on the contrary the ends of the cone will swing off to one side 45 of the true line of contact. This result is objectionable because it reduces the frictional driving contact at one end of the cone, thus causing a slippage which abrades the yarn and also tends to reduce the speed of 50 rotation of the package. This twisting of the cone on the drive-roll is further accentuated when the base of the cone-holder recedes from the drive-roll at a faster rate than that of the apex end. Fig. 7 illustrates 55 diagrammatically the effect of pivoting the opposite ends of the cone-holder on different axes. In this diagram, 4 is the axis of the arm A which supports the base end of the cone, and 5 is the axis of the arm E which 60 supports the apex end. The cone-holder C is represented by full lines as resting on the drive-roll D and the arcs 6-7 and 8-9 show the path of travel of the small end and large end of the cone respectively. From 6 the 65 center of the small end of the holder C

swings to 7 in winding the full package and the center of the large end swings from 8 to 9. Through this arrangement the axis of the cone will always be maintained in a plane coincident with the axis 10 of the 70 drive-roll D as indicated by the dot-and-dash lines 10-11 and 10-12. In other words the axis of the cone is maintained constantly coincident with the radial plane of the axis of the drive-roll and hence the line 75 of contact of the cone on the roll is always in alinement with the axis of the roll. In this way the cone is prevented from twisting laterally on the drive-roll during the growth in the winding and hence the driving 80 contact is maintained more uniform and constant.

Through the above described improvements I am enabled to wind a cone having a constantly increasing taper from its core 85 to its periphery without causing its nose end to be abnormally concaved. That is to say, the taper of the surface of the winding may be increased to the required extent without increasing the concavo-convexity of the ends 90 of the cone beyond what is required to provide the advantages desired. In addition, the preferred method of supporting the cone-holder as last described provides for a better driving contact between the cone and 95 the drive-roll and therefore results in a more uniform disposition of the coils of winding and less danger of abrading or stretching the yarn during its handling.

Various modifications other than those 100 herein shown might be made in the structure and arrangement of the winding-mechanism without departing from the spirit or scope of the invention; therefore, without limiting myself to the exact embodiment disclosed, 105 what I claim is:—

1. In a winding machine, the combination with a rotatable cone-holder on which the cone is wound with a gradually increasing taper on its surface, of means for traversing the yarn longitudinally of the holder, and means for continuously displacing the holder in the direction of its apex throughout the winding to regulate the disposition of the layers of yarn in their overlapped relation to prevent the nose of the cone from becoming abnormally concaved.

2. In a winding machine, the combination with a rotatable cone-holder, on which the cone is wound with a gradually increasing 110 taper on its surface, a drive-roll for rotating said cone-holder, and means for traversing the yarn longitudinally of the holder, of means for shifting the holder bodily in the direction of its apex throughout the building of the cone to regulate the disposition of the layers of winding and prevent their longitudinal displacement from causing an abnormal concavity at the nose end of the cone.

3. In a winding machine, the combination with a conical winding-mandrel, of means to rotate the mandrel to wind the yarn thereon, means to traverse the yarn longitudinally of the mandrel to dispose it in superimposed layers forming a tapered body with concavo-convex ends and with its periphery increasing in taper, and means to gradually displace the winding-mandrel 65 longitudinally in the direction of its apex to regulate the disposition of the layers of winding in relation to each other to prevent an extreme concavity at the nose of the cone.

10 15 4. In a winding machine, the combination with a conical cap-holder, of a drive-roll for rotating the holder, a reciprocating thread-guide for traversing the yarn on the holder to build a cone with its periphery gradually increasing in taper, and means influenced by the growth in diameter of the yarn wound on the holder to displace the latter in the direction of its apex during the building of the cone to regulate the overlap 20 25 of the layers of winding and prevent the formation of an abnormally concaved end at the nose of the cone.

5. In a winding machine, the combination with a rotatable cone-holder, of a drive-roll for rotating the cone-holder through peripheral contact with the yarn wound thereon, means to traverse the yarn longitudinally of the holder to deposit it in layers which gradually increase in taper 30 35 throughout the winding, means for allowing the holder to recede from the drive-roll during the increase in diameter of the winding, and means operated from said receding movement to shift the cone-holder longitudinally in the direction of its apex to regulate the disposition of the layers of winding to control the concavo-convex formation of the cone at its ends.

40 45 6. In a winding machine, the combination with a rotatable cone-holder, of a drive-roll for rotating the holder to deposit it in layers which gradually increase in taper throughout the winding, means to traverse the yarn on the holder, means for supporting the holder to adapt it to recede from the drive-roll as the winding increases in diameter, and means to shift said supporting-means laterally during the receding movement of the holder to gradually displace the cone in the direction of its apex longitudinally of the drive-roll.

50 55 60 7. In a winding machine, the combination with a rotatable cone-holder, of a drive-roll for rotating the holder, means to traverse the yarn on the holder to deposit it in

layers which gradually increase in taper throughout the winding, a pivoted arm for supporting the holder to adapt it to recede from the drive-roll as the winding increases in diameter, and means to displace the arm 65 along its pivot to shift the cone-holder in the direction of its apex to control the disposition of the layers of yarn in the cone to regulate the degree of concavo-convexity of its ends.

70 8. In a winding machine, the combination with a rotatable cone-holder, of a drive-roll for rotating the holder, means for traversing the yarn on the holder to deposit it in layers which gradually increase in taper 75 throughout the winding, a swinging arm for supporting the holder to adapt it to recede from the drive-roll with the growth in the winding, and a pin engaging a cam-slot on the arm to adapt the latter to be displaced laterally throughout its swinging movement to shift the cone-holder longitudinally in the direction of its apex during the building of the cone.

90 95 9. In a winding machine, the combination with a rotatable cone-holder, of a drive-roll for driving the holder, means for traversing the yarn on the holder, an arm pivoted on an axis at a distance from the drive-roll and carrying means for supporting one end of the cone-holder, and a second arm also pivoted at a distance from the drive-roll on an axis out of alignment with the axis of the first arm and carrying means for supporting the opposite end of the cone-holder, 100 said arms being independently movable to adapt their ends to swing in eccentric arcs whereby to support the cone-holder with its axis maintained constantly in a radial plane coincident with the axis of the drive-roll during the recession of the cone-holder from the drive-roll.

105 110 115 10. In a winding machine, the combination with a rotatable cone-holder, of a drive-roll for rotating the cone wound on the holder, means for traversing the yarn longitudinally of the holder, and two separate independently-movable arms for supporting the opposite ends of the cone-holder to adapt it to recede from the drive-roll as the cone increases in diameter, said arms being pivoted on different axes which are out of alignment to cause the ends of the holder to swing in eccentric arcs whereby its axis is maintained constantly in alignment with the axis of the drive-roll throughout its receding movement therefrom.

In testimony whereof I affix my signature.

GEORGE W. FOSTER.
